(57) **CLAIM**

The ornamental design for stackable and nestable receptacles, as shown and described.

DESCRIPTION

FIG. 1 illustrates a perspective view of a first embodiment of the stackable and nestable receptacles showing my new and ornamental design;

FIG. 2 illustrates a top plan view thereof;

FIG. 3 illustrates a bottom plan view thereof;

FIG. 4 illustrates a front view, the opposite end being a mirror-image thereof;

FIG. 5 illustrates an end view, the opposite end being a mirror-image thereof;

FIG. 6 illustrates, on an enlarged scale, a sectional view taken along line 6—6 in FIG. 2;

FIG. 7 illustrates a sectional view taken along line 7—7 in FIG. 6;

FIG. 8 illustrates a sectional view taken along line 8—8 in FIG. 2. The broken lines showing plural receptacles is for illustrative purposes only and form no part of the claimed design.

FIG. 9 illustrates a top plan view of another embodiment thereof; and,

FIG. 10 illustrates a side view, the opposite side being a mirror-image thereof.

1 Claim, 4 Drawing Sheets
